UNITED STATES PATENT OFFICE.

WILLIAM H. NICHOLS, OF PITTSBURGH, PENNSYLVANIA.

CHILL-MOLD.

1,336,260.

Specification of Letters Patent.

Patented Apr. 6, 1920.

Application filed August 18, 1919. Serial No. 318,379.

To all whom it may concern:

Be it known that I, WILLIAM H. NICHOLS, a citizen of the United States, and resident of Pittsburgh, in the county of Allegheny and State of Pennsylvania, have invented a new and useful Improvement in Chill-Molds; and I do hereby declare the following to be a full, clear, and exact description thereof.

- 10 My invention relates to chill-molds for casting rolls for rolling metal.
As it is well known these chill-molds are made of cast iron and the chill in the casting is obtained by the contact of the hot
15 metal in the mold with the inner walls of the mold, so that the metal for a certain distance in is converted into a hard white iron, while the interior of the casting will have the toughness which gives it its requisite
20 strength. When the metal is being poured into the chill the skin of the casting solidifies and the metal in the interior commences to part with its heat contracting away from the interior of the mold by so doing, the
25 mold at the same time absorbing the heat expanding away from the exterior of the casting. In order to prevent this too great and sudden expansion of the chill-mold, and at the same time reduce the necessity of making
30 it so thick, water has been used for cooling the chill and for this purpose a water-jacket has been cast in the walls of the chill through which the water is caused to circulate during the casting operation. Heretofore it has been customary where a water-
35 jacket is used to have the chill composed of several different sections, each with its own independent water-jacket and water supply, and these sections are laid one above the other to the full height of the chill. Where the chill was built up of these sections with independent water-jackets, there was always a portion of the chill which was not subject to the cooling action of the water, and
40 consequently an even chill could not be obtained, and, furthermore, defects in the surface of the chilled roll were present at the joints between the several sections.

The object of my invention is to provide
50 a chill-mold with a water-jacket cast integral therewith, extending continuously for the full height of the mold, and with a wall of uniform thickness so that the casting receives the same chilling effect throughout
55 its entire length.

To these ends my invention comprises the novel features hereinafter set forth and claimed.

In the drawing the figure illustrated is a vertical section of my improved chill illustrated in connection with the casting of a chilled-roll. 60

In the drawing the numeral 2 designates the lower box which is of the usual construction filled with sand 3 from which a wood pattern is molded which forms one of the couplings 4 and connections 5 of the roll. Supported on the box 2 is the chill 6 which is cylindrical in form and formed of cast iron. The chill 6 is cast with the water-jacket integral therewith, and in order to form this water-jacket in the casting of the chill an annular core is supported in the mold and the metal poured around the same, whereupon after the casting is cooled the 70 core is removed leaving the water-chamber 7 extending for practically the entire height of the chill, and with an open top which is closed by the annular plate 8 secured by bolts 9 to the flange 10 of the chill. 80

The upper end of the chill is cast with the neck portion 11 which forms a ledge 12 for the plate 8. By this construction the leakage of the water into the interior of the chill is prevented as there is no joint leading to 85 the interior wall of the chill.

The water is supplied to the water-jacket by the inlet 13 and is discharged by the outlet 14, whereby constant circulation of water is maintained. 90

Trunnions 15 are provided for the handling of the chill.

Resting on the upper end of the chill is the upper box 16 likewise filled with sand and in which the other coupling and neck of 95 the roll is cast. The customary head 17 is provided in which the impurities of the iron which rise to the top in casting are collected.

The casting gate 18 conducts the metal to the lower end of the mold all in the ordinary 100 manner.

When the metal is poured into the mold and fills the same the action of the chill will be to harden or solidify the metal which comes in contact with its inner walls and the metal in the interior commences to part with its heat and contracts away from the interior of the mold as it does so. The chill under conditions where no water-cooling is employed will become highly heated by ab- 110

sorbing the heat from the molten metal contained therein, and will expand away from the exterior of the casting. By circulating water through the water-jacket after this 5 expansion of the chill is counteracted by the cooling effect of the water, so that this drawing away of the chill from the exterior of the casting is largely avoided, and, furthermore, the thickness of the wall of the 10 chill would not be so great as where this heat has to be absorbed by the metal of the wall.

By having the water-jacket cast integral with the chill and extending for practically the full height of said chill, I obtain an even chilling effect, and all parts of the wall of the chill are equally cooled so that cracks in the roll due to unequal expansion and contraction of the walls of the 20 chill are avoided. Furthermore, by casting the chill with a water-jacket with an open top the core may be removed without difficulty, and the centering of the core in casting can be more accurately arranged for so 25 that an even thickness of chill-wall is obtained.

By setting the top plate 8 down on the ledge 12 at the upper end of the chill the

leakage of water into the interior of the chill is prevented.

30

What I claim is:—

1. A chill-mold having a water-jacket cast integral therewith forming a continuous water passage completely encircling the chill for substantially the entire height of said 35 chill.

2. A chill-mold having a water-jacket cast integral therewith forming a continuous water passage completely encircling the chill for substantially the full height of said 40 chill, having an open top, and a cover-plate secured to said chill.

3. A chill-mold having a water-jacket cast integral therewith, forming a continuous water passage for substantially the entire 45 height of the chill, having an open top, a neck-portion formed at the upper end of said chill forming a ledge and a cover-plate resting on said ledge secured to said chill.

In testimony whereof I, the said WILLIAM 50 H. NICHOLS, have hereunto set my hand.

WILLIAM H. NICHOLS.
